JOHN DRISCOLL, OF GYPSUM, KANSAS, ASSIGNOR OF ONE-HALF TO DAVID E. BENNETT,
OF GYPSUM, KANSAS.

CAR-COUPING.

1,158,189.

Specification of Letters Patent. Patented Oct. 26, 1915.

Application filed April 24, 1915. Serial No. 23,589.

To all whom it may concern:

Be it known that I, JOHN DRISCOLL, a citizen of the United States, and a resident of Gypsum, in the county of Saline and 5 State of Kansas, have invented a new and Improved Car-Coupling, of which the following is a full, clear, and exact description.

My invention relates to car couplers, and 10 has for its object the provision of a simple, strong and efficient coupler which will couple automatically and which can be easily and quickly uncoupled from the exterior of the car provided with the coupler by applying pressure to the coupler at a proper place 15 provided therefor.

With the above and other objects in view, the nature of which will more fully appear as the description proceeds, the invention 20 consists in the novel construction, combination and arrangement of parts as herein fully described, illustrated and claimed.

In the accompanying drawings, forming 25 part of the application, similar characters of reference indicate corresponding parts in all the views.

Figure 1 is a plan view of my coupler, partly in section, to show the details of construction; Fig. 2 is a section on line 2—2, 30 Fig. 1; Fig. 3 is a view similar to Fig. 1, the dotted line showing the coupler while the draw-bar is uncoupled; Fig. 4 is a side elevation of the draw-bar; and Fig. 5 is a cross section on line 5—5, Fig. 3.

Referring to the drawings, 6 represents a draw-head which has an end slot 7 for a draw-bar 8, which draw-bar has an opening 8'. Pivotedly mounted within the head and 35 extending across the slot 7 is a coupling bar 9 which is maintained in normal position by a resilient member 10 located within a bore 11 in the head 6. The axis of the resilient member 10 is in alinement with a pivot 12 of the coupling-bar 9, consequently, the 40 silent member 10 will bring the coupling bar 9 into normal position no matter which way it is swung. Slots 13 are provided on each side of the bore 11 to permit the coupling bar to swing in either direction.

Mounted pivotally within the head 6 is a 45 latch 14, the pivotal axis of the push bar being at right angles to the pivot of the coupling-bar 9. One end of the latch engages the coupling bar within the outer slot 13 (see 50 Fig. 2), so that when a pull is exerted on

the coupling bar the same will abut against the latch 14 and prevent the disengagement of the draw-bar from the coupling bar, thereby coupling the draw-bar to the draw-head. The other end of the latch 14 is engaged by a coil spring 15, which maintains 60 the engagement of the latch with the coupling bar 9.

The end of the latch engaged by the spring is provided with a push-button 16 projecting above the draw-head 6, whereby pressure may be applied to the latch and the end engaging the coupling-bar may be forced out of engagement therewith, thereby permitting the coupling-bar 9 to move into the 70 outer slot 13 when pull is exerted on the end of the coupling-bar located within the slot 7 of the head, thereby uncoupling the draw-bar from the draw-head. The coupling of the draw-bar with the draw-head is 75 automatic, as the movement of either the draw-bar or draw-head toward one another will cause the end of the coupling-bar 9 within the slot 7, when coming into engagement with the draw-bar 8, to swing, as indicated in dotted line in Fig. 1, until the draw-bar 8 clears the said end of the coupling bar, which, under the action of the coil spring 80 10, will automatically swing to its normal position to prevent a separation of the draw-head from the draw-bar, thereby coupling 85 the two.

To uncouple the draw-bar from the draw-head, pressure is applied to the button 16, whereby the latch 14 will be displaced, as indicated in dotted line in Fig. 2, permitting the coupling-bar 9 to swing when pull is exerted on the end of the draw-bar within the slot 7, as indicated in dotted lines in 90 Fig. 3.

I claim:

In a car coupling, the combination of a draw head having an end slot, a draw-bar having an opening adapted to engage said slot, a coupling bar pivotally mounted between its ends within said head and having one end thereof engaging the slot in the head, a compression spring resisting the movement of said coupling bar on its pivot whereby the end of the coupling bar is maintained within the slot, a pivotally-mounted latch within the head, a compression spring for forcing said latch into engagement with the end of the coupling bar not engaged in 100 the end slot of the head whereby the cou- 105 pling bar is maintained in normal position when the draw-bar is uncoupled, and a push-button 110 located on the end of the latch.

pling bar is normally prevented from movement on its pivot when a pull is exerted on the coupling bar, and a push-button associated with the latch whereby the same can 5 be forced to disengage the coupling bar, substantially as and for the purpose set forth.

In testimony whereof I have signed my

name to this specification in the presence of two subscribing witnesses.

JOHN DRISCOLL.
